UNITED STATES PATENT OFFICE

2,455,132

DOOR SECURING MEANS

Albert Matthews and Frank A. Gerlach, Cincinnati, Ohio, assignors to The American Laundry Machinery Company, Norwood, Ohio, a corporation of Ohio

Application December 21, 1944, Serial No. 569,134

6 Claims. (Cl. 220—55)

1

This invention relates to washing, cleaning or drying machines of that type employing a hollow cylinder or drum for containing the work, such as are used in laundries, dry cleaning establishments or the like. The invention has more particular relation to the cylinder doors and the means for fastening or holding them in closed or open position.

One object of the invention is to provide an improved arrangement in which the doors are secured in closed position both by a locking bolt and by a clamping band, both of which are operated by the same manually operated device.

Another object is to provide improved door securing means of the character described, in which the operating device is mounted on the door itself, rather than upon the cylinder.

Still another object is to provide a door locking bolt which also serves as an operator for a clamping or sealing band for the edge of the door.

Further objects of the invention in part are obvious and in part will appear more in detail hereinafter.

In the drawings:

Fig. 1 represents a front elevation of a drum or cylinder equipped with doors embodying the invention;

Fig. 2 is an enlarged detail elevation, corresponding to Fig. 1, showing the door closed;

Fig. 3 is a sectional elevation on the line 3—3, Fig. 2; and

Fig. 4 is a sectional view, on a larger scale, on the line 4—4, Fig. 2.

While the invention is capable of use on a variety of machines of different form adapted for different uses, such as dry cleaning washers, drying tumblers, churns, or the like, for convenience, and in no sense of limitation, it has been shown applied to the drum or cylinder of an industrial laundry washing machine.

The work holding cylinder 10 illustrated rotates on a horizontal axis in a stationary outer casing or tub (not shown) and, as shown in Vettorino 2,082,921, June 8, 1937, is provided with a perforate cylindrical wall 11 connecting the end heads 12 provided with end trunnions or lugs 13 adapted for mounting and rotation in suitable bearings (not shown) in the outer tub or casing, as is usual. The cylinder may also have its inner work holding space divided into several compartments or chambers by longitudinal or cross partitions, or both, requiring a plurality of doors, one such cross partition 14 being shown and requiring two doors. Since the locking and clamping devices are the

2

same on all doors, the description of one set will suffice for all.

The cylinder shown is provided with sliding doors 15, the curved side edges of which travel in guiding recesses 16 along the edges of the door opening, each door edge lying beneath a clamping band 17 having its upper end fastened, as at 18, to the body of the drum, and its lower end free and provided, on its inner face, with an end block 19.

The lower horizontal edge portion of the door is bent into channel form, as shown in Fig. 4 to provide an outwardly presented cavity 20 in which the locking devices are mounted, said devices preferably being of such form as to lie practically entirely within the cavity, thereby avoiding projections therefrom where possible, and also reducing the necessary clear space between the drum and outer casing or tub.

The locking devices, in the form shown, include, for each door, two locking bolts 21, each having a straight upper face 22 and an inclined lower face 23. The two bolts always move oppositely to each other, by relative motion of approach or separation, as the result of their simultaneous operation by the same operating mechanism. Preferably this is of the irreversible type. In other words operation of the mechanism will move the bolts in either direction, but force applied to the bolts and working in the opposite direction cannot affect or move the operating mechanism. As shown, each bolt has connected thereto a rod 24 provided with a hooked end portion 25 engaging the spiral scroll of a cam disc 26, capable of being turned by manipulation of handle 27, and of the same general form illustrated in detail in the above mentioned Vettorino Patent 2,082,921.

The free end of each clamping band is held down by suitable means, such as the head of a bolt 28 screwed through an elongated slot 29 into a stationary keeper member 30 mounted on the drum body.

Fig. 1 illustrates the left-hand drum door in fully closed position, in which its lower edge 30 enters a recess or groove 32 along the lower edge of the door opening. By rotating the handle 27 in the proper direction, the spiral scroll of cam 26 moves the rods 24 and locking bolts 22 outwardly, entering the ends of said bolts into the recesses or spaces between the stationary keeper member 30 and the end block 19 on the free end of the clamping band 17. The engagement of the straight surface 22 of the bolt with the stationary keeper member forms a positive lock preventing

opening movement of the door until the cam mechanism has been operated to release the lock bolts. At the same time, the inclined faces 23 of the bolts serve as wedges effective upon the movable end blocks 19 to move them downward in Fig. 1 and thus draw the clamping bands tightly against the side edges of the door and the adjacent portions of the cylinder body along which they travel.

Thus, in fully locked closed and locked position of the door, the door is not only locked, but its edges are tightly clamped and thereby are sealed to the edges of the door opening, preventing chatter and vibration of these relatively heavy metal parts such as might pinch and injure portions of the fabric or other material being operated upon if the doors were loose.

Operation of the handle 27 in the reverse direction withdraws the bolts from the locking recesses, and releases the clamping bands, permitting the door to be opened by sliding movement circumferentially of the drum or cylinder. Of course, if desired, the side edges of the door opening, at one or more points, may be provided with additional recesses, not shown, to enable the door to be releasably held and temporarily latched or locked in any partially open or fully open position, but, of course, without operation of the clamping bands, the sealing and clamping effect of which is unnecessary in these door positions.

Except for the clamping bands, which of course are mounted upon the cylinder body itself, all the locking and clamping parts are mounted upon and carried by the movable door. At the same time the same operating mechanism serves two purposes, first, to produce a locking effect, and second, to produce a clamping effect. Neither operation interferes with the other, but the operating mechanism is simplified and is thereby reduced in cost, with little likelihood of getting out of order in service.

Other advantages of the invention will be apparent to those skilled in the art.

What we claim is:

1. In combination, a rotatable work holding drum having a body provided with a charging opening in its cylindrical wall, a door for said opening slidably circumferentially of the drum, sealing bands lying over the side edges of the door and mounted upon the drum body, and means mounted upon and movable with the door for actuating said bands to seal the joints between the door side edges and drum body.

2. In combination, a rotatable work holding drum having a charging opening in its cylindrical wall, a door for said opening slidably circumferentially of the drum, the side edges of the door opening being provided with locking recesses, bolt members oppositely slidable on the door into and out of said recesses; an operator therefor, and clamping bands extending along the curved edges of the door opening and overlying the door edges, said bands each being fixed to the drum at one end and at the other end having an abutment block, each bolt being operatively associated with one of said blocks to tighten the band when the bolt is moved toward locked position.

3. In combination, a rotatable work holding drum having a charging opening in its cylindrical wall, a door for said opening slidably circumferentially of the drum, clamping bands mounted upon the drum and extending over the edges of the door, one end of each band being fixed and the other end being movable, door locking means, and common operating means for both the movable ends of said bands and said locking means mounted upon and movable with the door.

4. In combination, a rotatable work holding drum having a body provided with a charging opening in its cylindrical wall, a door for said opening slidably circumferentially of the drum, sealing bands lying over the side edges of the door and mounted upon the drum body, one end of each band being fixed and the other being movable, and means mounted upon and movable with the door for actuating the movable ends of said bands to seal the joints between the door side edges and drum body.

5. In combination, a rotatable work holding drum having a body provided with a charging opening in its cylindrical wall and with a locking recess at one side of said opening, a door for said opening slidably circumferentially of the drum, a sealing band lying over the side edge of the door and mounted upon the drum body, a locking bolt slidably mounted upon the door and adapted to enter said recess when the door is in closed position, and operating means for said bolt operatively associated with both the locking bolt and the band and thereby effective when operated both to advance said locking bolt into said recess to lock the door and to actuate said band to cause the same to seal the joint between the door side edge and the drum body.

6. In combination, a rotatable work holding drum having a charging opening in its cylindrical wall, a door for said opening slidably circumferentially of the drum, clamping bands mounted on the drum and extending circumferentially thereof and over the side edges of the door opening, one end of each band being fixed and the other movable, door locking means, and operating means mounted on the door and operatively associated with both the locking means and the bands and thereby effective upon them for simultaneously advancing said locking means to door locking position and moving the movable ends of the bands to tighten them upon the drum and along the side edges of the door when closed.
